CARRIER FREQUENCY TELEGRAPH SYSTEM

Georg Junga, Berlin-Lichtenberg, Germany, assignor to Siemens & Halske, Aktiengesellschaft, Siemensstadt, near Berlin, Germany, a corporation of Germany

Application July 22, 1937, Serial No. 154,976
In Germany July 24, 1936

10 Claims. (Cl. 178—66)

The invention relates to carrier-frequency telegraph systems, and more particularly to methods and means for rendering the reception of signals in such systems free from distortions due to amplitude variations of the incoming signals. Such amplitude variations tend to affect not only the amplitude of the signals ultimately reproduced in the receiver, but also the length of these reproduced signals.

10 It has been suggested to reduce these distortions by providing the receiver system with an automatic level control, and it is known to provide the grid or plate circuit of the receiving three-electrode tube of a telegraph system with 15 a resistance and condenser combination which effects such a level control. These circuit arrangements, although maintaining the amplitudes of the telegraph signals constant, have the disadvantage that they affect the envelope curve 20 and thus the length of the signals in the sense of a distortion. This distortion can be kept within desired limits only in the case of relatively small level variations.

25 The main object of the invention is to eliminate this disadvantage of carrier-frequency telegraph receivers. To this end, the invention provides for impressing on the receiver relay a voltage corresponding to the length which the incoming signals have at a predetermined fixed level. 30 This effect is obtained by level control means which are effective before and between the intervals during which the relay performs its switching operations. The operating and releasing points of the relay lie always at the same 35 place of the envelope curve and thus, independently of the level, have the same time distance so that the length of the signals remains unchanged and is independent of level variations.

40 The just-mentioned level regulation is obtained in the following manner. The incoming signals are impressed on the grid circuit of a receiving tube so that the grid voltage is varied in accordance with the signals. In this grid circuit, a control voltage is locally produced, thus obtaining a 45 superposed grid control which displaces the working range of the triode along its characteristic. The magnitude of this control voltage is made equal or approximately equal to half of that portion of the amplitude or intensity of the 50 incoming signals which exceeds a given base level. Since this excess amplitude, in general, is not constant, the magnitude of the control voltage is dependent upon the intensity or volume variations of the arriving signals.

55 Further, according to the invention, the periods during which the above-mentioned control voltage is effective are long as compared with one signal impulse in the case of closed circuit operation, or as compared with the spacing between

the impulses if open circuit operation is employed.

That amount of the excess amplitudes which is in excess of the control voltage involves a time constant which is of about the order of the time within which the amplitude of the incoming signals increases to its full value or decays to zero. In alternating current telegraph systems, this time is chiefly determined by the building-up 10 time of the filters. Due to this time constant, the adjustment of the amplitude to its normal value (E_{go}) becomes effective only after the signal has been transmitted without distortion to the receiving relay and has already become ineffective before the receiving relay makes the 15 next step.

The invention is particularly suitable for closed circuit operation but is also applicable with open circuit operation.

The above-characterized invention will be better understood from the drawings in which

Fig. 1 is a diagram showing the voltage and current curves in the grid and anode circuits of a triode in a carrier-frequency system according to the invention.

25 Figs. 2, 3 and 4 exemplify three different circuit arrangements with the aid of which the invention may be realized in practice and in accordance with Fig. 1.

30 While Figs. 5 and 6 are diagrams of explanatory nature for elucidating the matter illustrated in Figs. 1 and 2.

35 In the arrangements shown in Figs. 2, 3 and 4, U signifies an input transformer, the secondary winding s of which is connected in the grid circuit g of a three-electrode tube R . The anode circuit a of this triode is connected to a receiving relay ER which controls the telegraph circuit b . The terminals $-G$, O , $+A$ are to be connected to a voltage source furnishing the negative grid 40 voltage, the zero potential and the positive anode voltage respectively. The carrier-frequency modulated according to the telegraph signals to be transmitted is supplied to the primary winding p of transformer U .

45 If in arrangements of the above type the signal intensity were constant so that the grid voltage caused by the signals maintains a constant level E_{go} , the length of the signals and the silent intervals transmitted through the triode and indicated by the telegraph relay would maintain a correct value. In fact, however, the intensity of the incoming signals and hence the grid voltage controlled thereby are not constant. This actual grid voltage, therefore, may be considered 50 as being composed of the above-mentioned level voltage E_{go} plus an excess amplitude E_{gu} , so that the total grid voltage $E_g = E_{go} + E_{gu}$. This rise of the level above the value E_{go} would result, as stated before, in length distortions of the signals 55 60

indicated by the telegraph receiver. In order to avoid such distortions, the grid circuit of the triode shown in Fig. 2 contains an impedance combination R_1, R_2, C_1, C_2 , which, according to the invention, produces an automatic level control with the result that a correct length of the signals and intervals is maintained irrespective of variations in the volume or intensity of the incoming signals. The embodiments of Figs. 3 and 10 4 show other impedance combinations of similar function. The operation of these level controlling combinations and the requirements to be fulfilled with respect to the dimensioning of the individual combination elements, will become apparent from the following consideration.

The upper portion of the coordinate system of Fig. 1, having the zero point 0, shows the time curve of the anode current I_a , while the lower portion of the diagram shows the time curves of incoming signals.

To the left are plotted the voltages E_g in the grid circuit prior to the level regulation and to the right upwards the anode currents as function of the grid voltages of the level regulation. 25 It shall be assumed, for the sake of simplicity, that the voltages arising in the grid circuit are direct voltages and that the telegraph signals appear in the grid circuit already as rectified signals. It is of course obvious that the level control would function similarly if the telegraph signals arrived in the form of keyed alternating current signals. In this case the lines representing direct voltages would represent the envelope curve of an alternating current curve which, in 30 this case, would have to be supplemented symmetrically to the other side. The oblique line A/B represents diagrammatically the valve characteristic with its lower bend A, and OC represents the grid current curve. First it may be assumed that a voltage E_{go} is applied to the grid 35 so that the valve is modulated up to the lower bend A and that no anode current flows when no signal voltage is present.

In the case of closed circuit operation, during 40 the inoperative interval, a telegraph voltage is permanently effective at the grid. This voltage, at the lowest amplitude level, is equal in magnitude but of opposite direction as compared with the biasing voltage E_{go} and permits the maximum anode current to flow. This state continues 45 from time point 1 to point 2 and from 1' to 2' of the curve of the signal characteristic as shown in a solid line. The telegraph signal the curve of which is assumed for the sake of simplicity to be of trapezoid shape extending through the points 50 2, 4, 5, 6, 7, may commence at the time indicated by point 2. Consequently, in the anode circuit a curve according to points 2', 3', 4', 5', 6', 7' results. The responding limit of the receiving relay may lie on the line 3'-6'. In the case of a 55 correct level control it is necessary that the lengths of identical telegraph signals are also equal even if the level is different, this length being in this case equal to the distance 3'-6' or 60 3-6 assumed that the receiving relay is accurately adjusted to, and sufficiently maintains, the responding voltage level 3-6, a requirement which can easily be complied with with the modern, highly sensitive telegraph relays. Now when 65 the incoming signal in the grid circuit of the tube arrives not at the level E_{go} but at a higher level together with an additional excess voltage E_{gu} , with some of the hitherto known level control circuits, a curve of the telegraph signal according to curve 1, 2, 8, 9, 7 shown dash-dotted would

result. The greater length of the distance 18-19 compared with 3-6 represents a distortion because of the then longer duration of the period during which the relay responds to the telegraph signal.

Here the invention comes in. By the means described hereinafter, a control voltage is locally produced which is equal or approximately equal to half the excess amplitude. By virtue of this control voltage, the difference between excess 10 amplitude and control voltage is made to disappear before the receiving relay responds. It is thus achieved that the length of the signal approaches more nearly the ideal case, which it attains theoretically for the case in which the control voltage E_{gv} is equal to half the excess amplitude voltage E_{gu} . More particularly, with closed circuit operation, in the grid circuit of the tube a permanent grid voltage $E_g = E_{go} + E_{gv}$ is established as has been shown in Fig. 1 by the 15 line shown dotted throughout, which passes through the points 15-16. Thereby the telegraph signal which would originally have passed through the points 8-9, is displaced so that it actually passes through the points 10, 3, 11, 12, 6, 20 25 13. A geometric construction, which will be explained in the following, shows that all signals for which the relationship $E_g = E_{go} + E_{gv}$ is fulfilled, in which case $E_{gv} = \frac{1}{2}E_{gu}$, must pass 30 through the points 3 and 6. As a result, all signals received have equal lengths, even if the receiving amplitudes are different. The geometrical consideration which proves that under the conditions above mentioned the curve of the signal voltage always passes through points 3 and 35 6 regardless of the amplitude of the voltage, shall now be given with reference to Fig. 5. Fig. 5 shows a trapezoid ABCD. A second trapezoid ABEF is erected on the same base AB, the line EF having the same length as line CE. Dotted 40 lines EC and FD measure the difference in the heights of the two trapezoids. By bisecting this difference, the points E' and F' are obtained. The line E'F' now forms the basis for drawing another trapezoid A'B'E'F' which is made equal 45 to the trapezoid ABEF.

In the construction thus obtained, the slanting sides AD and BC of the original trapezoid ABCD and the slanting sides A'F' and B'E' of trapezoid A'B'E'F' bisect each other at points G 50 and H respectively. This results from the following. Due to the premises, AB and A'B' are parallel, and since trapezoids ABEF and A'B'E'F' are congruent, lines AF and A'F' must also be parallel. In the triangle ADF, the side DF is bisected at point F', also according to the premises. Since line A'F', going through midpoint F', is parallel to side AF of triangle ADF, the third side AC must be bisected by A'F'. That, further, line A'F' is bisected by line AC follows from the 55 facts that each of the two triangles AGA' and F'GD has its three sides parallel to the respective sides of the other triangle, and that the angle AGA' is equal to the angle F'GD so that both triangles are congruent.

The foregoing proves that all trapezoids ABEF of any possible height pass through the points G and H if displaced half the distance between their top side EF and that of the original trapezoid CD. The present invention, dealing with 70 signal voltages of approximately trapezoidal curve shape, utilizes this geometrical law by applying a displacement voltage E_{gv} which is equal, or approximately equal, to half the excess modulation voltage E_{gu} . As a result, the signals re- 75

produced in the receiver have always the desired length regardless of the value of the excess voltage.

Reverting now to Fig. 2, it will be seen that the impedance combination R_1, R_2, C_1, C_2 , there shown, represents the simplest circuit diagram for realizing the operating conditions established with reference to Fig. 1, i. e. for producing the above-mentioned additional control voltage E_{gv} .

10 R_1 and R_2 designate a resistance arrangement connected in the grid circuit of the triode R in parallel to condenser C_1 . The resistance arrangement is tapped in the middle so that $R_1=R_2$. From this center tapping the resistance R_2 is 15 bridged by the condenser C_2 . The grid, in known manner, acts upon the anode circuit of the valve R and thus upon the polarized receiving relay ER , a definite position of which is in known manner effected by applying a magnetic bias 20 through a second winding. It is necessary, for an advantageous control, that the time constant of the resistance-condenser combination R_2 and C_2 is large compared with the time constant of the resistance condenser combination (R_1+R_2) .

25 C_1 .

The functioning of the circuit arrangement follows from a consideration of Fig. 1. When the signal commences, the full grid voltage $E_{go}+E_{gu}$, in consequence of the small time constant of the 30 combination $(R_1+R_2)C_1$, drops from point 14 to point 15 and thus to the voltage $E_{go}+E_{gv}$ which is maintained by the condenser C_2 . This voltage remains in existence during the duration of the signal because of the large time constant of the combination C_2-R_2 . Only after the relay has responded does the voltage rise again along the curve 16-17 in consequence of the charge on the condenser C_1 , the voltage then reassuming the full grid voltage value.

40 The diagram shown in Fig. 6 serves to further indicate the relation of arrangement of Fig. 2 to the trapezoidal voltage curves shown in Fig. 1. The elements S, g, C_1, C_2, R_1 , and R_2 , in Fig. 6, are identical with the similarly designated elements in Fig. 2. The legends in Fig. 6 identify the voltages occurring in the arrangement by referring to the voltage curves shown in Fig. 1. Accordingly, the voltage across the secondary S of the input transformer corresponds to the original curve 2, 8, 9, 7 of Fig. 1. The voltage having the curve 14, 15, 16, 17 lies across resistor R_1 . The time constant of the resistance combination $C_1 R_1$ is very small so that the voltage decreases quickly from 14 to 15. Across the end of the regulating network, i. e. between the grid conductor g and the pole $-G$, appears the regulated output voltage corresponding to curve 2, 10, 3, 11, 12, 6, 13, 7.

Fig. 3 shows another advantageous circuit arrangement for practising the method according to the invention. In this circuit arrangement, the resistance R_1+R_2 which lies in parallel with the condenser, is divided at the ratio

$$65 \frac{R_1+R_2}{R_2} = \frac{1}{\sqrt{0.5}}$$

and the condenser C_2 is charged through another resistance $R_3=R_1$. The condenser C_2 is, therefore, charged, when the charge is built up, with 70 $\sqrt{0.5}$ times the excess amplitude voltage E_{gu} . When discharging condenser C_2 loses $1-\sqrt{0.5}$ times its charging potential through voltage drop at the resistance R_3 so that in the grid circuit there is again a control voltage E_{gv} effective 75 which is 0.5 times the excess voltage E_{gu} . Com-

pared with the circuit arrangement according to Fig. 2, the circuit arrangement according to Fig. 3 is of advantage in that, in the case of closed circuit operation, it is sooner in operating condition and that, in the case of variations in intensity of the incoming signals, the desired level is sooner established. This follows from the fact that the time for charging the condenser C_2 is about half the time constant required for discharging the condenser. Lastly, this circuit arrangement has the advantage that in the case of continuously transmitted signal combinations of one polarity, the most favorable displacement voltage is unilaterally displaced to a substantially smaller extent than with the circuit arrangement according to Fig. 2.

In the circuit arrangement according to Fig. 4, the condenser C_2 forms the terminating link of a chain network, the attenuation of which is so dimensioned that $\sqrt{0.5}$ times the excess voltage E_{gu} is effective at the displacement condenser C_2 , when charged. When discharging through the chain network, this voltage is reduced again to $\sqrt{0.5}$ times the amount so that in the grid circuit there is again effective, as control voltage, a voltage equal to 0.5 the excess amplitude. In the grid circuit lies the condenser C_1 for the normal level control, in parallel with which lies the resistance of the chain network. The insertion of the condensers C_3 and C_4 has the purpose to still better balance the effect of unfavorably dimensioned telegraph signals. This is of advantage in cases where telegraph signals are transmitted continuously which comprise for example 4 + impulses and 1 - impulse or, 35 1 - impulse and 4 + impulses, an operating condition which without the additional condensers may lead to a shifting of the permanently adjusted control voltage E_{gv} from its normal position.

I claim as my invention:

1. In a communication system having a receiving terminal provided with a circuit for compensating for the variations in amplitude level of the transmitted signals in a signal transmission circuit, the method of regulating the amplitude of the incoming signals which consists in producing a locally generated control voltage approximately equal to one half of the excess amplitudes, and impressing said control voltage on 45 said receiving terminal so as to thereby effect a distortion-free signal reception.

2. In a carrier-frequency telegraph system having a receiving grid-controlled tube connected in a transmission circuit for compensating for the variations in amplitude level of the transmitted signals, the method of regulating the amplitude of the incoming signals which consists in producing a locally generated control voltage approximately equal to a magnitude having a 50 given fixed relation to the excess amplitudes, and impressing said control voltage on said receiving terminal so as to thereby effect a distortion-free signal reception.

3. In a carrier-frequency telegraph system for 55 closed circuit operation having a receiving terminal provided with a transmission circuit and a grid-controlled receiving tube in said circuit for compensating for the variations in amplitude level of the transmitted signals, the method of 70 regulating the amplitude of the incoming signals which consists in producing a locally generated control voltage approximately equal to one half of the excess amplitudes, and impressing said control voltage on said receiving terminal, and 75

maintaining after a signal has commenced said control voltage effective during a period which is long compared with the duration of one pulse of the signals.

5. In a carrier-frequency telegraph system for open circuit operation having a receiving terminal provided with a transmission circuit and a grid-controlled receiving tube in said circuit for compensating for the variations in amplitude 10 level of the transmitted signals, the method of regulating the amplitude of the incoming signals which consists in producing a locally generated control voltage approximately equal to one half of the excess amplitudes, and impressing said 15 control voltage on said receiving terminal, and maintaining after a signal has ceased said control voltage effective during a period which is long compared with one spacing of the longest duration between two pulses of the telegraph 20 signals employed.

5. A carrier-frequency receiver system having a transmission circuit for compensating for the variations in amplitude level of the transmitted signals, a receiver relay connected with said circuit, a grid-controlled tube having its anode circuit connected so as to form part of said transmission circuit, a grid circuit for impressing on the grid of said tube a bias voltage in accordance 25 with the incoming signals, and reactive means connected with said grid circuit for locally producing a control voltage approximately equal to one half of the excess amplitudes, said reactive means having a time constant in the order of 30 magnitude of the duration of the individual pulses of said signals to maintain said control voltage effective during a period having at least the duration of one pulse of the signals.

6. A carrier-frequency receiver system having a 40 transmission circuit for compensating for the variations in amplitude level of the transmitted signals, a receiver relay connected with said circuit, a grid-controlled tube having its anode circuit connected so as to form part of said transmission circuit, a grid circuit for impressing on the grid of said tube a bias voltage in accordance 45 with the incoming signals, and an impedance combination connected in said grid circuit to effect a distortion-free signal transmission by 50 locally producing a control voltage, said impedance combination including two series-connected resistors of equal resistance forming a voltage divider, and a condenser connected with one of said resistors so as to be charged in the intervals 55 between subsequent signals with a voltage approximately equal to one half of the excess amplitudes, whereby said condenser after a signal has ceased acts upon the grid of said tube with its full charging potential.

60 7. A carrier-frequency receiver system having a transmission circuit for compensating for the variations in amplitude level of the transmitted signals, a receiver relay connected with said circuit, a grid-controlled tube having its anode circuit connected so as to form part of said transmission circuit, a grid circuit for impressing on the grid of said tube a bias voltage in accordance 65 with the incoming signals, and an impedance combination connected in said grid circuit to effect a distortion-free signal transmission by locally producing a control voltage, said impedance combination including a voltage dividing resistance 70

network and at least one condenser connected in said network so as to be charged between subsequent signals with $\sqrt{0.5}$ times the excess amplitudes of the signals received, whereby said condenser after cessation of a signal acts upon the 5 grid of said tube with $\sqrt{0.5}$ times its charging potential.

8. A carried-frequency receiver system having a transmission circuit for compensating for the variations in amplitude level of the transmitted 10 signals, a receiver relay connected with said circuit, a grid-controlled tube having its anode circuit connected so as to form part of said transmission circuit, a grid circuit for impressing on the grid of said tube a bias voltage in accordance 15 with the incoming signals, and means arranged in said grid circuit for imposing in response to the signal voltage on the grid of said tube a control voltage approximately equal to one half of the excess amplitudes of the signals received, said 20 means having a time constant designed to render said control voltage effective during a period beginning after and ending before the variation of the grid voltage caused by a received signal passes 25 through the responding value of said relay.

9. A carrier-frequency receiver system having a transmission circuit for compensating for the variations in amplitude level of the transmitted signals, a receiver relay connected with said circuit, a grid-controlled tube having its anode circuit connected so as to form part of said transmission circuit, a grid circuit for impressing on the grid of said tube a bias voltage in accordance 30 with the incoming signals, and an impedance combination connected in said grid circuit for locally producing a control voltage approximately equal to one half of the excess voltage amplitudes, said impedance combination comprising 35 two series-connected resistances of equal magnitudes, a condenser connected in parallel to said two resistances, and a second condenser connected in parallel to only one of said resistances so as to be charged in the intervals between subsequent signals with about one half of said excess 40 voltage amplitudes, the time constant of the part 45 combination consisting of said latter condenser and the one resistance parallel connected thereto being greater than the time constant of the part combination consisting of said two series-connected resistances and said first condenser. 50

10. A carrier-frequency receiver system having a transmission circuit for compensating for the variations in amplitude level of the transmitted signals, a receiver relay connected with said circuit, a grid-controlled tube having its anode circuit connected so as to form part of said transmission circuit, a grid circuit for impressing on the grid of said tube a bias voltage in accordance 55 with the incoming signals, and a chain network connected in said grid circuit for preventing signal distortions by producing a local control voltage, said chain network containing one or more T members composed of resistances and linked together with one another and with said grid circuit by capacitors and having another capacitor forming the termination of said chain, the total attenuation of said chain being designed to effect a charge of said latter capacitor between subsequent signals with $\sqrt{0.5}$ times the excess 60 voltage amplitudes of the signals received. 70

GEORG JUNGA.
